(57) **CLAIM**

The ornamental design for a programmable power strip, as shown and described.

DESCRIPTION

FIG. 1 is a front elevational view of a programmable power strip of the present invention;

FIG. 2 is a rear elevational view of the programmable power strip of FIG. 1;

FIG. 3 is a left side elevational view of the programmable power strip of FIG. 1;

FIG. 4 is a right side elevational view of the programmable power strip of FIG. 1;

FIG. 5 is a top plan view of the programmable power strip of FIG. 1; and,

FIG. 6 is a bottom plan view of the programmable power strip of FIG. 1.

The broken lines showing numbers and letters in FIG. 1 are for illustrative purposes only and form no part of the claimed design.
